UNITED STATES PATENT OFFICE.

FREEMAN BARNEY, OF GRAND HAVEN, MICHIGAN, ASSIGNOR TO THE CHALLENGE MACHINERY COMPANY, OF GRAND HAVEN, MICHIGAN, A CORPORATION OF MICHIGAN.

DESIGN FOR A STANDARD.

Application filed July 25, 1927. Serial No. 22,860. Term of patent 7 years.

To all whom it may concern:

Be it known that I, FREEMAN BARNEY, a citizen of the United States, residing at the city of Grand Haven, in the county of Ottawa and State of Michigan, have invented a new, original, and ornamental Design for Standard, of which the following is a specification, reference being had to the accompanying drawing, forming a part thereof.

The standard is particularly intended as a support for machinery but is suitable for general use.

The figure is a perspective view of a standard showing my new design.

I claim:

The ornamental design for a standard, as shown.

FREEMAN BARNEY.
